UNITED STATES PATENT OFFICE.

ARTHUR REGINALD ANGUS, OF PALL MALL, LONDON, ENGLAND.

RAILWAY SAFE-RUNNING DEVICE.

Application filed April 14, 1913. Serial No. 761,042.

(GRANTED UNDER THE PROVISIONS OF THE ACT OF MARCH 3, 1921, 41 STAT. L., 1313.)

To all whom it may concern:

Be it known that I, ARTHUR REGINALD ANGUS, a subject of the King of Great Britain, and a resident of the Royal Automobile Club, Pall Mall, S. W. 1, in the county of London, England, solicitor, have invented a certain new and useful invention entitled Improvements in or Relating to Railway Safe-Running Devices, of which 10 the following is a specification.

This invention is intended to form one of a series devised by the same inventor for the protection of trains against collision one with another by means of devices, arranged 15 partly on the train and partly on or about or adjacent to the railway tracks and having for object, inter alia, the elimination of certain dangers arising from the personal equation, that is, from human weakness or 20 fallibility and comprises the various features hereinafter set forth in the claiming clauses hereof.

In the examples of apparatus according 25 to this invention hereinafter described there are placed on or about or adjacent to the railway tracks suitable track contacts comprising a top contacting surface composed of some suitable electrically conductive material and mounted on some suitable non- 30 conductive material such as wood or the like. These track contacts are of two kinds which may be referred to as "warning" and "stop" contacts respectively and are such that when the contact shoe or similar device 35 carried on a locomotive or train comes into contact therewith it is displaced. The stopping contacts effect a greater displacement of the shoe than the warning contacts. The contacts have their ends suitably ramped 40 to enable interaction with the contact shoe on a train to be effected without shock or jar. Connected with these track contacts are suitable polarized switching instruments or the like preferably placed in a signal box 45 or the like which are adapted to be operated in the manner hereinafter described by a train entering a block section in such a manner as to prevent another train from entering the section while upon leaving the 50 section the switching instruments are set in such a position as to allow another train to enter the section.

The railway tracks are divided into suitable sections or blocks certain sections pref-

erably intersecting or overlapping (herein- 55 after called "intersecting") other sections each section being provided with contacts so that a train may operate upon instruments relating to the section so as to close or open either end of a section from the 60 same track contact or so as to open or close both ends of a section at the same time. The closing or opening of a section may be effected by suitable relays.

In order to enable trains running on up or 65 down journeys to differently affect the same switching instruments from the same track contacts the reversing lever or the like on the locomotive for reversing the direction of running of the locomotive is connected by 70 suitable levers, rods, links, or the like with a suitable generator pole changing device on the train so that when the locomotive is running say on the down journey the positive pole of the generator will be connected 75 to the contacting device on the train and upon contact thereby with a track contact current from the generator will flow there- 80 through, the return being effected either through the wheels and frame of the locomotive or train or through a return contacting device on the train (corresponding contacts being used in this case on or about or adjacent to the railway tracks) and when the train is running in the opposite direc- 85 tion on the same track the negative pole of the said generator will be connected to the said contacting device and upon contact thereby with the said track contact current will flow in the reverse direction through 90 the track contact.

When a locomotive or train changes its direction of running by means of a turn-table, triangle, loop, or the like a commutator switch or the like must be operated 95 by the driver or the like so as to change the connections or circuits on the locomotive or train in a manner corresponding to the reverse direction of running, and means for ensuring that the driver shall move his 100 commutator switch are therefore provided according to this invention.

The invention is illustrated by the accompanying drawings which represent by way of example apparatus in accordance therewith.

Fig. 1 is a diagrammatic view of the apparatus used on a locomotive or train.

Figs. 2 and 3 show two different methods of arranging and interconnecting the track contacts and polarized switching instruments relating to one section of the railway track.

5 Figs. 4 and 4' show the arrangement of the track apparatus for intersecting sections.

Fig. 5 shows a modified method of arranging and interconnecting the track contacts 10 and switching instruments relating to a section whereby by the use of quick acting electromagnets a single line wire connecting the two instruments of a section is enabled to be employed for operating either one or 15 the other of the instruments.

Fig. 6 shows an arrangement by which it is automatically ensured that a driver on 20 leaving a turntable, loop, triangle, or the like shall correctly set the train apparatus for the reversed direction of running.

A suitable contacting device comprising a shoe 10 (Fig. 1) is attached to and insulated from any suitable part of a locomotive, brakevan, or other suitable vehicle.

25 The shoe 10 is adapted to be given different displacements by contact with track contacts such as 1, 2, 3, 4, 5 and 6 (Figs. 2, 3, etc.) placed on or about or above the railway tracks and when not in contact with a track 30 contact is returned to its lowest or normal position by gravity and by a spring 7, although it may be returned to its normal position by one or more springs only or by gravity only. Attached to and insulated 35 from the contact shoe 10 is a resilient bridging contact member 8, comprising fingers adapted to bridge when the shoe is in its outmost contact position (hereinafter referred to as "its lowest position") the contact 40 plates 9, 11, 12, so as to complete the circuits of the generator 14 by wire 15 contacts 16 and 17 wire 18 contact plate 9 bridging member 8 and thence by (a) contact plate 11, wire 19, coil of solenoid 20, contacts 31 45 (if bridged by handle 30) and wire 21 back to the generator thereby energizing solenoid 20 and holding closed the valve 22 controlling means either for shutting off the motive power of the locomotive or for applying the 50 brakes on the train or both; and by (b) contact plate 12 wire 23 coils of solenoid 24 and magnet 29 contacts 31 (if bridged by the lever 30) and wire 21 back to the generator 14, thereby energizing the solenoid 24 and 55 keeping closed the valve 25 so as to prevent the danger whistle 26 from being blown and also energizing the magnet 29 and attracting its armature so as to maintain the miniature visual signal 28 in the clear or off 60 position.

When the shoe 10 comes into contact with a warning contact such as 1 or 6 (Figs. 2 and 3) it is displaced to such an extent that one of the bridging contact fingers passes off the contact plate 12 thereby breaking

there as far as the bridging contact member 8 is concerned the connection between the contacts 9 and 12, and so opening the circuit relating to the solenoid 24 and magnet 29 so that if the said circuit is not otherwise maintained the plunger of the solenoid 24 is forced out by whatever pressure may be acting on the valve 25 and the danger whistle 26 is blown and the miniature signal 28 is also raised into the on or danger position. 75

When the shoe 10 comes in contact with a stop contact such as 2, 3, 4, or 5 (Figs. 2 and 3) it is displaced to a greater extent than when displaced by a warning contact so that the bridging contacts are also raised 80 clear of the contact plates 9 and 11, thereby breaking the circuit of the solenoid 20 so that if the said circuit is not otherwise maintained the plunger of the solenoid 20 is forced out by whatever pressure may be acting 85 on the valve 22 and the lever 30 (used for replacing the plunger) is moved so that the circuits of the generator 14 and the coils of solenoids 20 and 24, and magnet 29 are broken at the contacts 31. 90

It is intended that the opening of the valve 22 which is normally held closed by the plunger of the solenoid 20 should allow the admission of fluid pressure such as of steam air gas or the like to a suitable cylinder the piston of which is adapted to shut off the motive power of the locomotive and should also allow or cause the operation of means for applying the brakes on the train. Either the shutting off of the motive power 100 or the application of the brakes or both may be used for stopping the train. 105

If the commutator switch 100 and the reversing gear switch 41 are in the positions shown in Fig. 1—that is to say, in the positions for the down journey—when the shoe 10 comes into contact with either a warning or a stopping track contact which has been rendered electrically conductive in the manner hereinafter explained current will flow 110 from the generator 32 on the locomotive by wire 33 coils of magnet 34 wire 35 arm 36 and contact 37 of the commutator switch 100 wire 42 arm 43 and contact 44 of the reversing gear switch 41 (which is adapted 115 to be moved by the movement of the reversing lever of the locomotive) wire 48 shoe 10 the track contact and thence through an external or track circuit back by the rails to the frame of the locomotive wire 49 contact 46 and arm 45 of the reversing gear switch wire 50 contact 39 and arm 38 of the commutator switch and wire 51 to the generator 32. 120

If the conditions of the circuits and apparatus connected thereto are normal the current which flows will be of a predetermined normal value and will cause the coils of the magnet 34 to attract the armature 52 against gravity and the spring 53 so as to 125

contact with the insulated contacts 54 and 55 and at the same time to break contact with contact 56.

By a current of predetermined normal value is meant one which can energize the magnet 34 sufficiently to enable it to attract its armature 52 (so as to contact with the contacts 54 and 55) but not sufficiently to enable it to raise the armature 52 to such an extent as to break contact between the contacts 16 and 17 by lifting the pivoted lever 70 against gravity and a spring 71.

Contact of the armature 52 with the contacts 54 and 55 provides paths in substitution for those broken at contact plates 9, 11 and 12, through branch wire 57, armature 52, contacts 54 and 55, and wires 58 and 59 respectively, to the coils of solenoid 20 and solenoid 24 and magnet 29 so that warning and stopping operations on the train are restrained. At the same time the circuit of the coil of solenoid 60, which is normally completed from generator 14 by wire 15 contacts 16 and 17 wire 18 branch wire 57 armature 52 contact 56 wire 61 coils 60 and wire 21, is broken at the contact 56 thus de-energizing the solenoid 60 and allowing its plunger to be forced out by whatever pressure may be acting on the valve 62 so that the line clear whistle 63 is blown.

From the foregoing description it will be seen that the apparatus on the locomotive comprises two generators 14 and 32 (though if desired a common generator may be used); an electromagnet 34 adapted when normally energized to complete substitutional circuits through the normally energized restraining coils 24, 29 and 20 and at the same time to break the circuit of the coil of the solenoid 60; a commutator switch 100; and a reversing gear switch 41 which is adapted to be operated by the movement of the reversing gear of the locomotive and which, when in the position shown in Fig. 1—that is to say for the down journey—and when the commutator switch is also in the position shown, connects the positive pole of the generator 32 through the electromagnet 34 to the shoe 10 and the negative pole of the generator 32 to the frame of the locomotive and so to the rails.

When the reversing gear switch is moved over for the locomotive to run on the up journey the connections of the poles of the generator 32 to the shoe 10 and to the frame of the locomotive are reversed—that is to say the shoe 10 is connected to the negative pole of the generator and the frame of the locomotive to the positive pole of the generator through the electromagnet 34 and at the same time a resistance 64 is inserted into the circuit.

The commutator switch 100 which must be operated when the locomotive is turned round on a turntable, triangle, or the like

performs functions similar to those of the reversing gear switch 41—that is to say reverses the connections of the generator 32 to the shoe 10 and to the frame of the locomotive and at the same time inserts a resistance 65 into the circuit.

When the commutator switch 100 and the reversing gear switch 41 are both moved over from the positions shown in Fig. 1 the locomotive apparatus will be set for running in the same direction as when in their present positions—that is to say for the down journey—but in this case both of the resistances 64 and 65 (which are equal) would be in the circuit in series when there should be no resistance at all in the circuit. For this reason insulated short-circuiting plates are placed on the arms of those two switches which when both the switches are over short circuit the resistances 64 and 65 by contact with suitable contacts 66, 67, 68 and 69.

It will thus be seen that a locomotive running on the down journey will always have its contact shoe 10 connected to the positive pole of the generator and also that there will be no resistance such as 64 or 65 in series but that for the up journey the shoe 10 will always be connected to the negative pole of the generator and one or other of the resistances 64 and 65 will always be connected in series.

When a current exceeding the predetermined normal value flows through the coils of the electromagnet 34 the armature 52 is attracted with sufficient force against the insulated contacts 54 and 55 to lift the arm 70 against gravity and the spring 71, so as to break contact between the contacts 16 and 17 so that the paths to the coils of 60, 24, 29 and 20 are broken and both whistles 63 and 26 are blown, the miniature signal 28 raised to the on or danger position and the motive power shut off or brakes applied or both.

At the two ends of a section (Fig. 2) are placed warning contacts 1 and 6 respectively followed by two stop contacts 2, 3 and 5, 4, respectively. At the two ends of the section there are also polarized switching instruments X and Y, the armatures 73 and 74 of which make contact with contacts 75, 76 and 77, 78, respectively, when in what may be termed the open position, and with contacts 79 and 80 respectively when in the closed position. These armatures are each adapted to remain in the open or closed position, as the case may be, when moved into such position by the flow of current through their respective magnet coils. Each armature 73 and 74 also carries insulated contact plates 81 and 82 respectively adapted to contact with contacts 83 and 84 when the armatures are in the closed position. There are also resistances

85, 86, 87, 88, and 89, 90, 91, 92, connected as shown. In the leads of track contacts 2 and 5 are included quick acting polarized relays 251 and 261, the armatures 253 and 263 of which always maintain contact with the contacts 254 and 264 except only when the current flows through their coils in a particular direction. In this case they are caused to come into contact with contacts 10 255 and 265 and to leave contacts 254 and 264, spring contact devices being provided such that contact with the contacts 255 and 265 will be made before the contact is broken with contacts 254 and 264 respectively.

15 When the line is clear and a train running on the down journey comes into contact with track contact 1, the switches X and Y being in their closed positions, the circuit comprising the generator 32 and 20 shoe 10 hereinbefore described is completed through track contact 1, wire 72 contact 83 insulated contact 81, wire 93, and a path through resistance 89, wire 94, coil 95 of the polarized switching instrument Y in parallel with a path through resistance 91, contact 80, and armature 74, to earth and thence by wire 99 to the rails and the frame of the locomotive and so back to the generator 32 as hereinbefore described. The direction of 30 flow of the current through the coil 95 is such that the armature 74 is moved into the open position thereby breaking the parallel path through resistance 91 at contact 80 and completing a path parallel to that through the coil 95 through resistance 90 wire 102 contact 78 and armature 74 to earth. The values of the resistances 89 and 90 are so chosen with relation to the 35 resistance of the coil 95 that their combined values when arranged in this manner allow current of the predetermined normal value to flow from the generator 32 through the electromagnet 34 which accordingly attracts its armature so as to complete the 40 substitutional circuits of the coils 24, 29 and 20 and thereby to restrain the warning and stopping operations and to allow the line clear whistle 63 to be blown.

45 The current which flows until the armature 74 has moved into contact with contact 78 is not of predetermined normal value, but it does not affect the warning apparatus on the train because the ramped end of the track contact 1 is of such length 50 that the shoe 10 is not fully raised thereby until the armature 74 has moved into contact with contact 78. A similar explanation 55 will apply throughout the following description wherever the circumstances are 60 similar.

65 It will thus be seen that the armature 74 must contact with contact 78 to allow normal current to flow through the electromagnet 34. Should it, however, remain in the closed position, thereby remaining in

contact with the contact 80 and maintaining the parallel path for the current through the resistance 91 and thus providing a reduced combined resistance, a current exceeding the normal would pass 70 through the coils of the electromagnet 34 and a warning operation would accordingly be effected on the train. Should the armature 74 stick midway or should it for some other reason not complete the circuit of 75 the parallel resistance 90 at the contact 78, the resultant resistance thus provided for the current flowing through the coils of the electromagnet 34 would be higher than normal because, whereas normally the path 80 comprising the wire 94 and the coil 95 is paralleled by the path comprising the resistance 90, the contact 78, and the armature 74, the former path would not in this case be paralleled at all, consequently a current of less than the normal strength would pass 85 through the coils of electromagnet 34 so that the armature 52 would not be attracted and a warning operation would accordingly be effected on the train. The armature 74 must thus be definitely moved into the open position to enable a train in contact with contact 1 to obtain clearance. The movement of the armature 74 into the open position also breaks at the contact 84 the connection of the track contact 6 to the rails by wire 103 contact 84 contact 82 wire 104 etc., and of the track contact 5 to the rails by wire 260 coils 261 armature 263 contact 265 wire 103 contact 84 etc., so that the track contacts 6 and 5 are rendered non-conductive for a train on the up journey and a train coming into contact with them on the up journey will accordingly be 90 warned and stopped in the manner herein 95 described. Consequently a train on the down journey is warned if it has failed to render it impossible for a train on the up journey to enter the section at the other end. 100

105 When the train comes into contact with track contact 2 on the down journey the circuit hereinbefore described and comprising the generator 32 and the shoe 10 is completed through the track contact 2 wire 250 the coils of the polarized relay 251 armature 110 253 contact 254 resistance 257 wire 99 the rails and the frame of the locomotive. 115

120 The direction of current which flows through the coils 251 is such that the armature 253 is moved to contact with contact 255, thereby connecting up track contact 2 through the coils 251 to the contact 83 of the main switch X and the circuit is then 125 the same as previously described for track contact 1. If the main switch X is closed the armature 74 of Y is maintained in the open position and the train obtains clearance but if the main switch X is not closed or the armature 74 is not maintained in the open position it will be warned and 130

stopped on coming into contact with the track contact 2. Also if the armature 253 does not move but maintains contact with contact 254 normal current does not flow 5 through the coils of electromagnet 34 on the train and the train is warned and stopped as the resistance 257 although correct for the trains on the up journey is not so for trains on the down journey. 10 When the train running on the down journey comes into contact with track contact 3 current flows as before from the generator 32 to the shoe 10 track contact 3 a path through resistance 85, and the coil 97 15 of the polarized switching instrument X, in parallel with a path through resistance 86, contact 79, and armature 73, wire 99 to the rails and thence through the frame of the locomotive back to the generator 32 as hereinbefore described. The armature 73 is thereby moved into the open position so as to break the parallel path through resistance 86 at contact 79, and to contact with the contact 75 to form a path, parallel to 20 that through the coil 97 through resistance 87 contact 75 and armature 73 to the rails. The values of the resistances 85 and 87 in relation to that of the coil 97 are such that when arranged in this manner normal current 25 flows from the generator 32 through the coils of electromagnet 34 on the train and so restrains the warning and stopping operations and allows a line clear intimation to be given as before described. It is essential 30 in order to obtain this result that the armature 73 should contact with the contact 75; for, should it remain in the closed position contacting with contact 79 as shown in Fig. 2 the resistance 86 would be included 35 in parallel circuit thereby lowering the combined resistance opposed to the passage of current so that current exceeding the normal value would pass through the coils of the electromagnet 34 on the train and so break the circuit of the generator 32 at contacts 16 and 17 and cause the blowing of both whistles 63 and 26 the shutting off of the motive power and the application of the brakes. Moreover should the armature 73 40 stick midway or for some other reason not effect contact with contact 75 the resistance 87 would not be switched into parallel and resultant resistance thus provided for the current flowing through the coils of the electromagnet 34 would be higher than normal, 45 because, whereas normally the path comprising the resistance 85 and the coil 97 is paralleled by the path comprising the resistance 87, the contact 75, and the armature 73, the former path would not in this case be paralleled at all; consequently a current of less than the normal strength would pass through the coils of the electromagnet 34 so 50 that the armature 52 would not be attracted and the warning and stopping operations 55

would be performed on the train. For the train at contact 3 to obtain clearance the armature 73 must therefore be moved into the open position. When it is in this position connection is broken as far as a train on 70 the down journey is concerned at the contacts 83 and 81 between the track contacts 1 and 2 and the rails so that a train coming into contact with them will be warned and stopped as herein described. 75

It will therefore be evident that a train cannot pass into the section over the track contacts 1, 2, and 3 without placing the switches X and Y at the ends of the section 80 into the open position and thereby rendering non-conductive as described the track contacts at each end of the section.

When the train, continuing on the down journey, comes into contact with track contact 4 current flows as before from the generator 32 to the shoe 10 and track contact 4 and thence by wire 105 to the coil 96 of the polarized switching instrument Y in parallel with a path through resistance 92, contact 77, and armature 74, and by wire 106 to the 90 rail and thence to the frame of the locomotive and back to the generator 32 as previously described. The armature 74 is thereby moved into the closed position and normal current flows from the generator 32 95 through the coils of the electromagnet 34 on the train and so allows the operation of the line clear intimations and restrains the warning and stopping operations on the train. 100

When the train on the down journey comes into contact with track contact 5 the circuit of the generator 32 is completed as before described through the shoe 10 track contact 5, wire 260 the coils of the polarized relay 261, armature 263 contact 264 resistance 267 wire 106 the rails and the frame of the locomotive and allows normal current to pass through the electromagnet 34. The direction of current through the coils 261 is 110 such that the armature 263 maintains connection with the contact 264 and does not contact with contact 265 thereby including the resistance 267 in circuit. Normal current flowing the warning and stopping operations on the train are restrained and line clear intimations given. 115

When the train comes into contact with track contact 6 on the down journey the circuit of the generator 32 is completed as before described through the shoe 10 track contact 6 wire 103 contacts 84, 82, wire 104, the coil 98 of the polarized switching instrument X in parallel with a path through resistance 88, contact 76, and armature 73, 120 to earth wire 106 the rails and thence back to the generator through the frame of the locomotive as hereinbefore described. It will be seen that unless the armature 74 has been moved to close the contacts 84, 82, this 125 130

circuit will not be completed and the train will accordingly be warned on coming into contact with track contact 6.

The armature 73 of the instrument X is thus moved to close the contacts 83 and 81 and so leaves the section clear for another train on the down journey to enter.

When a train running in the opposite direction—that is to say on the up journey 10 —comes into contact with the track contacts relating to this section the following operations will successively be performed:—

When the train comes into contact with track contact 6 current will flow from the generator 32 by wire 33 coils of electromagnet 34 wire 35 arm 36 and either by way of (a) contact 37 of the commutator switch 100 wire 42 arm 43 and contact 46 of the reversing gear switch which has been moved 20 over for running on the up journey (the commutator switch being still in the position shown in the figure) or by way of (b) contact 39, wire 50, arm 45, and contact 46 (if the commutator switch 100 but not the reversing gear switch 41 has been moved) and in either case, by way of wire 49, the frame and rails, wire 106 to earth coil 98 of the polarized switching instrument X, wire 104 contacts 82 and 84 (which are closed if the line is clear) wire 103 track contact 6, shoe 10 wire 48 thence by way of (a) wire 107 resistance 64 contact 47 and arm 45 of the reversing gear switch 41 wire 50 contact 39 and arm 38 of the commutator switch 100 30 (if the reversing gear switch 41 but not the commutator switch 100 has been moved) or by way of (b) the contact 44, the arm 43, the compensating resistance 65, the contact 40, and the arm 38 (if the commutator switch 100 but not the reversing gear switch 41 has been moved), and, in either case, by way of wire 51 to the generator 32. It will be seen that the direction of the current through the coil 98 is reversed so that the armature 40 45 73 is moved into the open position to contact with contacts 75 and 76 and in doing so places the resistance 88 into parallel with the coil 98 through the armature 73 and contact 76.

50 The combined value of the resistance of the coil 98 and the resistance 88 as thus arranged is now less than the value of the resistance of the local circuit from track contact 6 when the armature 73 is moved 55 into the closed position as when operated by a train running out of this section on the down journey. For this purpose the compensating resistance 64 or 65 is placed in the circuit which then consequently offers 60 the same resistance to the passage of the current from generator 32 as when a train running on the down journey comes into contact with this track contact and completes a circuit in which there is no compensating resistance 64 or 65. Current of

predetermined normal value therefore flows through the coils of electromagnet 34 allowing the line clear intimations to be given and restraining the warning and stopping operations on the train. It is essential for 70 this result to be obtained that the armature 73 should contact with the contact 76 so as to complete the circuit of the resistance 88 for should it not do so (as for example should the armature 73 remain in the closed position or stick midway) current of less than normal strength would flow through the coils of electromagnet 34 and a warning operation would consequently be effected on the train owing to the fact that, whereas normally the coil 98 is paralleled by the path comprising the resistance 88, the contact 76, and the armature 73, the coil 98 would not in this case be paralleled at all so that the resistance thus provided for the current flowing through the coils of the electromagnet 34 would be greater than the normal.

When the train comes into contact with track contact 5 on the up journey current will flow as just described from the generator 32 through the coils of electromagnet 34 the frame of the locomotive the rails wire 106 resistance 267 contact 264 armature 263 the coils 261 wire 260 track contact 5 shoe 10 returning to the generator 32 through the compensating resistance 64 or 65 and wire 51. The current through the coils 261 is thus reversed and causes the armature 263 to move into contact with contact 265 and thus break the connection with contact 264. The circuit from track contact 5 through the coils 261 and contact 84 is then the same as just described with reference to track contact 6 so that the armature 73 of X is maintained in the open position if the main switch 105 Y is closed. Otherwise the train will be warned and stopped when in contact with track contact 5. Moreover should the armature 263 remain in contact with contact 264 instead of moving to contact with contact 265 the resistance of the circuit of the generator 32 would be greater than normal owing to the inclusion in the circuit of the resistance 64 or 65 and current of predetermined normal value would not flow through the coils of electromagnet 34 so that warning and stopping operations would be effected on the train.

When the train comes into contact with track contact 4 on the up journey current 120 will flow as described from the generator 32 through the coils of electromagnet 34 to the frame of the locomotive the rails wire 106 coil 96 of the polarized switching instrument Y, wire 105 to track contact 4 and shoe 10 returning to the generator 32 through the compensating resistance 64 or 65 and wire 51. The current through the coil 96 is thus reversed and the armature 74 accordingly moved into the open position to 125 130

contact with contacts 77 and 78 and so to form a path parallel to that through the coil 96 through armature 74 contact 77 and resistance 92. Normal current therefore flows through the coils of electromagnet 34 and results in the giving of line clear intimations and the restraining of warning and stopping operations on the train. Should the armature 74 not contact with contact 77 and so not complete the parallel circuit of the resistance 92 (for example should it remain in the closed position or stick half way) current of less than the predetermined normal value would flow through the coils of electromagnet 34, and consequently warning and stopping operations would be performed on the train owing to the fact that whereas normally the coil 96 is paralleled by the path comprising the armature 74, the contact 77, and the resistance 92, the coil 96 would not in this case be paralleled at all so that the resistance thus provided for the current flowing through the coils of the electromagnet 34 would be greater than the normal.

Thus it will be seen that the train on the up journey on entering the section and passing over contacts 6, 5 and 4, is unable to proceed unless it has moved both armatures 73 and 74 to the open positions thereby rendering the track contacts at each end of the section non-conductive and thus preventing the entrance of any other train into the section.

Continuing on the up journey the train comes into contact with track contact 3 so that current flows as before from the generator 32 to the coils of electromagnet 34 to the frame of the locomotive the rails wire 99 coil 97 of the polarized switching instrument X in parallel with a path through armature 73, contact 75, and resistance 87, resistance 85, track contact 3, shoe 10 compensating resistance 64 or 65 and back to the generator 32. The current through the coil 97 is thus reversed and the armature 73 is moved into the closed position to break the parallel path through resistance 87 at contact 75 and to contact with contact 79 thus switching the resistance 86 into parallel circuit with the coil 97 and resistance 85, and the circuit with one or the other of the compensating resistances 64 and 65 effectually included therein offering normal resistance to the passage of current therethrough normal current flows through the electromagnet 34 causing line-clear intimations to be given and the restraining of warning and stopping operations on the train.

It will be seen that should the armature 73 not contact with contact 79 (as for example should it remain in the open position or stick midway) current of less than the normal value would pass through the coils of electromagnet 34 and warning and stop-

ping operations would accordingly be performed on the train owing to the fact that (a) if the armature 73 were to remain in the open position and the track portion of the circuit consequently have, as hereinbefore explained with reference to the down journey, such a resistance as to cause current of normal strength to flow through the coils of the electromagnet 34 only if neither of the compensating resistances 64 and 65 were effectually included in circuit, the resistance then provided for the current flowing through the coils of the electromagnet 34 would, on account of the effectual inclusion in circuit of one or the other of the compensating resistances, be greater than the normal and (b) if the armature 73 were to stick midway, the coil 97 would not be paralleled at all, so that the resistance provided in this case for the current flowing through the coils of the electromagnet 34 would also be greater than the normal.

When the train comes into contact with track contact 2 on the up journey the circuit of the generator 32 is completed through the electromagnet 34, the frame of the locomotive, the rails wire 99 resistance 257 contact 254 armature 253 coil of polarized relay 251 wire 250 track contact 2, shoe 10 and thence as before described. The direction of flow of the current through the coils 251 is thus reversed and the armature 253 maintains contact with contact 254. The resistance 257 is such that normal current flows through this circuit and the train obtains clearance.

When the train comes into contact with contact 1 on the up journey before passing out of the section current will flow as before from the generator 32 to the coils of the electromagnet 34 and the frame of the locomotive the rails wire 99 to earth coil 95 of the polarized switching instrument Y, and wire 94, in parallel with a path through armature 74, contact 78, wire 102, and resistance 90, resistance 89, wire 93, contacts 81 and 83, wire 72, track contact 1, shoe 10, and compensating resistance 64 or 65 back to the generator 32. The current through the coil 95 is thus reversed and the armature 74 is moved into the closed position to contact with contact 80. The resistance 91 is thus switched into circuit and normal current flows through the coils of the electromagnet 34 thereby producing line clear intimations and restraining warning and stopping operations on the train. It will be seen that this circuit is not completed unless the contacts 83 and 81 have been closed as should have been done by the train when in contact with track contact 3 when running on the up journey and if this circuit is not completed the train will be warned.

Moreover should the armature 74 not effect contact with contact 80 and therefore

fail to switch the resistance 91 into parallel circuit as for example should it remain in the open position or should it stick midway in each case current lower in value than the predetermined normal value would flow through the coils of electromagnet 34 and the train would be accordingly warned, owing to the fact that (a) if the armature 74 were to remain in the open position and 10 the track portion of the circuit consequently have, as hereinbefore explained with reference to the down journey, such a resistance as to cause current of normal strength to flow through the coils of the electromagnet 15 34 only if neither of the compensating resistances 64 and 65 were effectually included in circuit, the resistance then provided for the current flowing through the coils of the electromagnet 34 would, on account of the 20 effectual inclusion in circuit of one or the other of the compensating resistances, be greater than the normal and (b) if the armature 74 were to stick midway, the coil 97 would not be parallel at all, so that the 25 resistance provided in this case for the current flowing through the coils of the electromagnet 34 would also be greater than the normal. From the foregoing description it will be seen that on entering a section for 30 either direction of running a locomotive or train is unable to proceed unless it definitely places the armatures 73 and 74 in certain definite positions. The vital condition is that a train must always protect itself in 35 front and behind by breaking the contact at 83, 81, and at 84, 82, and it will be seen from the foregoing description that on every occasion when a train ought to break contact at one of those pairs of contacts 40 it will be either warned or stopped or both if it fail to do so.

An alternative method of arranging and interconnecting the track contacts relating to a section with the polarized switching instruments relating thereto is illustrated by Fig. 3 the distinguishing feature of the arrangements being that resistances 109, 110, 111 and 112 are placed in series with the coils 98, 97, 96 and 95 and are adapted to be entirely short-circuited for certain definite positions of the armatures 73 and 74. The coils 98, 97, 96, 95 of the polarized switching instruments are shown permanently shunted by resistances 113, 114, 115 and 116 but if desired those shunts may be omitted.

With this modified arrangement when the line is clear and a train running on the down journey comes into contact with track 60 contact 1, the circuit of the generator 32 is completed to the shoe 10 as before described thence by track contact 1, wire 72, contacts 83 and 81, wire 93 to the coil 95 (shunted by the resistance 116) of the polarized switching instrument Y, and thence

by a path through wire 236, contact 117, and armature 74, in parallel with resistance 112 to earth, thence by wire 99 to the rails and by the frame of the locomotive back to the generator 32 as hereinbefore described. The armature 74 is moved into the open position to break the parallel path through contact 117 and to contact with contacts 77 and 78, and completes a path parallel to that through the coil 95 and resistances 116 and 112, through resistance 13, contact 77, and armature 74 to earth. The combined value of these resistances and of the coil 95 as thus arranged allows current of the predetermined normal value to flow from the generator 32 through the electromagnet 34 which attracts its armature 52 and so completes the substitutional circuits of the coils 24, 29 and 20 thus restraining the warning and stopping operations and allowing the line clear whistle 63 to be blown. It is evident that unless the armature 74 completes the circuit of the resistance 13 through contact 77, current of normal value will not flow through the coils of electromagnet 34 with corresponding results on the locomotive. The armature 74 must therefore be moved into the open position for the train to obtain clearance so as to break contact between the contacts 84 and 82 and render the track contacts 6 and 5 non-conductive.

When the train comes into contact with track contact 2 on the down journey the circuit of the generator 32 is completed as before described through the shoe 10, track contact 2, wire 250, the coil of the polarized relay 251, armature 253, contact 254, resistance 257, wire 99, the rails, and the frame of the locomotive.

The direction of current through the coils 251 is such that the armature 253 is moved to contact with contact 255, thereby connecting up track contact 2 through the coils 251 to the contact 83 of the main switch X and the circuit is then the same as previously described with reference to track contact 1.

If the main switch X is closed the armature 74 of switch Y is maintained in the open position and the train obtains clearance but if not it is warned and stopped when in contact with track contact 2. Also if the armature 253 is not moved but maintains contact with contact 254 normal current does not flow through the coils of electromagnet 34 and the train is warned and stopped since the resistance 257 is correct for the up journey but is not so for the down journey.

When the train running on the down journey comes into contact with track contact 3 current flows as before from the generator 32 to the shoe 10 thence by wire 235 to the coil 97 of the polarized switching instrument X shunted by the resistance 114, a

path through wire 123, contact 79, and armature 73, in parallel with resistance 110 wire 99 to the rails and by the frame of the locomotive back to the generator 32 as hereinbefore described. The armature 73 is moved into the open position to break the parallel path through contact 79 and to contact with contacts 75 and 76 thus completing the circuit of the resistance 118 through contact 76 and armature 73 and paralleling it with the coil 97 and the resistances 114 and 110 so that current of normal value flows from the generator 32 through the coils of electromagnet 34 thus operating the line clear intimations and restraining the warning and stopping operations. Moreover it is evident that the armature 73 must contact with the contact 76 to complete the circuit of resistance 118 in order to obtain this desired result for otherwise current of predetermined normal value will not flow through the coils of electromagnet 34 and warning and stopping operations will be effected on the train. The armature 73 must therefore be moved into the open position for the train to obtain clearance so as to break contact between contacts 83 and 81 of switch X and render the track contact 1 non-conductive and the track contact 2 non-conductive for following trains.

It is thus evident that the trains cannot pass into the section over the track contacts 1, 2 and 3 without opening the contacts 83, 81, 84, 82 at each end of the section and thereby rendering the track contacts at each end non-conductive as hereinbefore described.

When the train continuing on the down journey comes into contact with track contact 4 current flows as before from the generator 32 to the shoe 10 and track contact 4, thence by wire 105 to the coil 96 of the polarized switching instrument Y, shunted by resistance 115, a path through wire 122, contact 78, and armature 74, in parallel with resistance 111, wire 106 to the rails and by the frame of the locomotive back to the generator 32 as previously described. The armature 74 is moved into the closed position thus breaking the parallel path through contact 78 and completing the circuit of the resistance 119 by wire 120 contact 80, and armature 74, so that current of normal value flows from the generator 32 through the coils of electromagnet 34 thus operating the line clear intimations and restraining the warning and stopping operations on the train.

It is evident that normal current will not flow through the coils of electromagnet 34 unless the armature 74 is in the closed position and completes the circuit of the resistance 119.

When the train comes into contact with track contact 5, the circuit of the generator

32 is completed as before described through the shoe 10 track contact 5, wire 260, the coils of the polarized relay 261, armature 263, contact 264, resistance 267, wire 106, the rails, and the frame of the locomotive so that normal current passes through the electromagnet 34. The direction of current through the coils 261 is such that the armature 263 maintains connection with the contact 264 and does not contact with contact 265. The warning and stopping operations on the train are accordingly restrained and line clear intimations given.

When the train comes into contact with track contact 6 on the down journey the circuit of the generator 32 is completed as before through the shoe 10 track contact 6, wire 103, contacts 84 and 82, wire 104 to the coil 98 of the polarized switching instrument X shunted by resistance 113, resistance 109 to earth wire 106 to the rails and back by the frame of the locomotive to the generator 32 as hereinbefore described. It will be seen that unless the armature 74 has been moved on contact with track contact 4, to close the contacts 84 and 82 of switch Y, this circuit will not be completed and the train will not obtain clearance. The armature 73 is moved to close contacts 83 and 81 of switch X thereby rendering the track contacts 1 and 2 conductive and leaving the section clear for another train to enter. When in this position the armature 73 contacts with contacts 237 and 79 and so completes the circuit of the resistance 121 and allows current of normal value to flow from the generator 32 through the coils of the electromagnet 34. It is evident that the armature 73 must complete the circuit of resistance 121 to obtain this desired result and if it does not do so an abnormal current flows through the coils of electromagnet 34 with corresponding results on the train.

When a train is running in the opposite direction—that is to say, on the up journey—the operation of the apparatus is reversed in a manner similar to that previously described with reference to Fig. 2 for the up journey the normal resistances of the circuits for line clear being arranged to be less than the normal track resistances for the down journey by the value of each compensating train resistance 64 and 65.

From the foregoing description it will be seen that on entering a section for either direction of running, a train is unable to proceed unless it places the armatures 73 and 74 in certain definite positions. It is vital that the train should be unable to proceed unless it has protected itself in front and behind by breaking the contact at the contacts 83, 81 and 82, 84, and thus as hereinbefore described to render the track contacts at each end of the section non-conductive as hereinbefore stated.

It will be seen from Figs. 2 and 3 if a train passing out of a section is in contact with the last track contact 6 thereof at the same time as another train entering the same section is in contact with the first track contact 1 thereof the train leaving the section will first free the section by operating the instrument X at the entering end of the section so as to give the entering train clearance and the entering train will then set the instrument at Y so as to block the section and so cause the train which is leaving the section to receive a warning. The last mentioned train will thus receive an automatic signal that another train is following it up closely.

In Figs. 4 and 4' is shown a continuous stretch of railway track provided with apparatus arranged according to this invention and comprising contiguous sections U and W the adjacent ends of which are intersected by a similar section V. The track contacts and switching apparatus relating to these sections may for the sake of convenience be mentioned as *a* and *b* for section U, *c* and *d* for section W, and *e* and *f* for section V, while *k* and *g* pertain to similar intersecting sections the other ends of which are not included in the figure.

The figures are intended to represent the method whereby the "interlocking" of sections is effected so that should a train on one section have satisfactorily operated both the switching instruments relating to that section when in contact with the track contacts relating to them and subsequently for some reason or other should any of the armatures of these switching apparatus leave the positions in which they have been placed thereby endangering the safety of the train it will be warned and stopped on interacting with the track contacts relating to another intersecting section with which the section in question is interlocked and the train will thus be unable to proceed. Furthermore these figures show how, by the use of intersecting sections a definite space interval is always maintained between all trains on the same line whether running in opposite directions or in the same direction.

These ends are achieved by threading the line wires relating to a section through contacts placed on the armatures of the polarized relays or the like relating to the intersecting section. For example a train running on the down journey will first come into contact with the track contacts at *a* and should as herein described place the armature 74 at *b* in the open position and its definite occupation of this position can be checked either by the method of electrical balance hereinbefore described with reference to Fig. 2, as is indicated in Figs. 4 and 4', or by the method of electrical balance described with reference to Fig. 3.

Should it not do this when in contact with the track contacts 1 and 2 at *a* it would be warned and stopped. It being assumed that this operation has been performed satisfactorily and that the train has obtained clearance over track contacts 1 and 2 at *a* it will on continuing its down journey come into contact with the track contacts at *k* and *e* and when in contact with the contacts 1 and 2 at *e* a circuit will normally be completed as follows—from the generator 32 on the locomotive through the coils of the electromagnet 34 to the shoe 10 as previously described, thence when the shoe 10 is in contact with track contact 1 at *e* directly to the wire 72 or when the shoe 10 is in contact with track contact 2 at *e* indirectly (as hereinbefore described with reference to Fig. 2) to the wire 72, thence by wire 72, contact 83, contact 81 to main line wire 93 threaded through contact 125 at *b* and insulated contact 126, coil 95 of the polarized relay at *f* to earth and thence by wire 99 at *e* through the rails and the frame of the locomotive back to the generator 32.

It will thus be seen that if the armature 74 at *b* is in the open position (as it should be) so that its insulated plate 126 contacts with contact 125 the required circuit will be completed and the train will obtain clearance on contacts 1 and 2 at *e*. But should for any reason the armature 74 at *b* not have remained in the open position after the train has interacted with the track contact 2 at *a* the required circuit would not be completed and the train would be warned and stopped on interacting with track contacts 1 and 2 at *e*.

Continuing the train will come into contact with track contact 3 at *e* moving the armature 73 at *e* into the open position so that when the train is in contact with either of the track contacts 5 and 6 at *b* it will complete the circuit of the generator 32 through the coils of electromagnet 34 shoe 10 track contact 5 or 6 whichever be in contact with the shoe 10, thence to the wire 103 indirectly in the case of track contact 5 (as hereinbefore described with reference to Fig. 2) or directly in the case of track contact 6, thence by way of the wire 103, the contact 84, and the insulated plate 82 to the main line wire 104 threaded through contacts 127 and 128 coil 98 to earth at *a* and by wire 106 at *b* through the rails and the frame of the locomotive back to the generator 32 but will not do so unless the armature 73 at *e* has remained in the open position. On entering section W and coming into contact with track contacts 1 and 2 at *e* a circuit is completed through the locomotive's apparatus as before described, thence when the shoe 10 is in contact with track contact 1 at *e* directly to the wire 72.

or when the shoe 10 is in contact with track contact 2 at *c* indirectly (as hereinbefore described with reference to Fig. 2) to the wire 72, thence by the wire 72, the contacts 83 and 81 line wire 93 to contact 125 at *f* contact 126 wire 93 to the coil 95 of the polarized relay at *d* to earth wire 99 at *c* the rails and back by the frame of the locomotive to the generator 32. If the armature 74 at *f* is in the open position as it should be after the train has made contact with track contacts 1 and 2 at *e* this circuit is completed and the armature 74 at *d* is moved into the open position. But should, 10 for any reason the armature 74 at *f* not be in the open position this circuit would not be completed and the train would be warned and stopped on track contacts 1 and 2 at *c*.

Similar operations take place at *f*, *g* and 20 *d* and therefore do not need further description.

It will thus be seen that the sections are 25 mutually interlocked inasmuch as the train is warned and stopped should the results of the functions it has performed on one section not be maintained when it comes into contact with the track contacts relating to an intersecting section.

The method of maintaining a definite 30 space interval between any two trains will also be seen from Figs. 4 and 4'. For example if two trains are travelling in opposite directions on the same line the one on the down journey on coming into contact 35 with track contacts 1 and 2 of section U at *a* will render the track contacts 5 and 6 at *b* non-conductive by moving armature 74 at *b* to the open position. The other train travelling on the up journey and interacting with 40 track contacts 6 and 5 of section V at *f* will render the track contacts 1 and 2 at *e* non-conductive by moving the armature 73 at *e* to the open position. The down train will therefore be warned and stopped on coming 45 into contact with track contacts 1 and 2 at *e* and the up train on coming into contact with track contacts 6 and 5 at *b* and these respective stopping contacts 2 at *e* and 5 at *b* and all corresponding similar contacts are 50 placed a distance apart equal to double the maximum braking distance plus a percentage, so that not only is a following train brought to rest before it can collide with a train in front but trains travelling in opposite directions are brought to a standstill before colliding with one another.

Fig. 5 shows another modification of this invention in which quick-acting electromagnets 214 and 215 are used for the purpose of cutting out one of the polarized relays X or Y while operating the remaining one.

A train equipped with apparatus such as shown in Fig. 1 and running on the down 60 journey first comes into contact with track

contact 1 and the circuit of the generator 32 is completed through track contact 1 wire 216 contacts 83 and 81 wire 217 coils of magnet 214 (thereby attracting the armature 218 and breaking at contact 219 70 the circuit of the coil 97 of the polarized relay X) wire 220 branch wire 221 armature 222 contact 223 wire 224 the coil 96 of the polarized relay Y to earth wire 99 the rails and the frame of the locomotive. The armature 74 is thus moved into 75 the open position thereby breaking at contact 84 the circuit of the track contacts 5 and 6.

On coming into contact with track contact 2 on the down journey the circuit of the generator 32 is completed as before described through the shoe 10 track contact 2 wire 250 the coils of the polarized relay 251 armature 253 contact 254 resistance 257 80 wire 99 the rails and the frame of the locomotive. The direction of current through the coils 251 is such that the armature 253 is moved to contact with contact 255 thereby connecting up track contact 2 through the coils 251 to the contact 83 of the main switch X and the circuit is then the same as previously described with reference to track contact 1.

Should the main switch X be closed the 95 armature 74 would thus be maintained in the open position and the train would obtain clearance otherwise it would be warned and stopped on effecting contact with track contact 2. Also should the armature 253 not 100 move but maintain contact with contact 254 normal current would not flow through the coils of the electro-magnet 34 and the train would be warned and stopped since the resistance 257 is correct for the up journey 105 but not for the down journey.

On coming into contact with track contact 3 on the down journey the circuit of the generator 32 is completed through the wire 225 the coil 98 of the polarized relay X wire 110 99 the rails and the frame of the locomotive thus causing the armature 73 to be moved into the open position and thereby breaking at contact 83 the circuit of the track contacts 1 and 2. The correct placing of the armatures 73 and 74 must be checked by either of the methods shown in Figs. 2 and 3 or by an equivalent arrangement.

The train has now passed completely 120 within the section and has protected itself from collisions both in the front and in the rear by opening the switches 84, 82 and 83, 81 respectively.

Continuing on the down journey so as to 125 leave the section the train comes into contact with track contact 4 and completes the circuit of the generator 32 by track contact 4 wire 226 the coil 95 of the polarized relay Y wire 106 the rails and the frame of the locomotive, thus causing the armature 74 to 130

be moved into the closed position so as to complete the circuit of the track contacts 5 and 6 at contacts 82, 84.

When the train comes into contact with track contact 5 the circuit of the generator 32 is completed as before described through the shoe 10 track contact 5 wire 260 the coils of the polarized relay 261 armature 263 contact 264 resistance 267 wire 106 the rails and 10 the frame of the locomotive. The direction of current through the coils 261 is such that the armature 263 maintains connection with the contact 264 and does not contact with contact 265 so that normal current passes 15 through the electromagnet 34 and the warning and stopping operations on the train are thus restrained and line-clear intimations given.

When the train comes into contact with track contact 6 on the down journey the circuit of the generator 32 is completed through wire 227 the contacts 84 and 82 wire 228 the coils of magnet 215 (thereby attracting the armature 222 and breaking the circuit to the coil 96 at contact 223) wire 220 branch wire 229 armature 218 contact 219 wire 230 the coil 97 of the polarized relay X to earth wire 106 the rails and the frame of the locomotive. The armature 73 is accordingly moved into the closed position to complete the circuit of track contacts 1 and 2 at contacts 83 and 81 and the section is thus left clear for another train to enter.

A train running on the up journey sends out current of the reverse polarity through the track contacts and the various operations are successively performed in the correct order but from the contacts in the opposite order—that is to say on track contacts 6 and 5 the armature 73 is moved to or maintained in the open position respectively and on track contact 4 the armature 74 is moved into the open position while on leaving the section on contact with track contact 3 the armature 73 is moved into the closed position and on contact with track contact 1 the armature 74 is moved into the closed position.

When a locomotive or train changes its direction of running upon a turntable triangle loop or the like its commutator switch 100 must be operated by the driver so as to change the connections of the generator and switch the compensating resistance 65 into and out of circuit and so enable the locomotive to operate the track apparatus in the correct manner for the reversed journey and to obtain clearance if it should do so when in contact with the track contact, despite the fact that the reversing gear switch has not been moved. It is essential that this operation should be done and checked at the turntable, triangle, loop, or the like itself as otherwise the locomotive might be able to run some distance on the main line back

in the opposite direction without being stopped.

Means for automatically compelling a driver to move his commutator switch must therefore be provided and such means are 70 illustrated with reference to a loop in Fig. 6 of the drawings.

Track contacts 1 and 2 are placed adjacent to the loop and connected as shown in the figure. 75

The coils 402 and armature 407 are parts of an ordinary polarized relay or switching instrument placed in the lead from track contact 1, the armature of which is normally in such a position as to keep its insulated 80 contact plate 417 in contact with contact 416 and the coils 401 and armature 410 are parts of a polarized relay placed in the lead from the track contact 2, the armature 410 of which is normally in such a position as to 85 keep its insulated contact plate 405 in contact with contact 403.

The operation of the apparatus is as follows:—

The train entering the loop on the down journey first effects contact with track contact 2 (which is a stopping contact) and completes the circuit of the generator 32 carried on the train through the coils of electromagnet 34 (Fig. 1) shoe 10 track 95 contact 2 wire 400 the coils 401 resistance 412 wire 411 contact 406 armature 407 (if in the closed position) wire 408 the rails and back by the frame of the locomotive to the generator 32 the circuit not including either of 100 the compensating resistances 64 or 65. The direction of the current through the coils 401 is such as to move the insulated contact plate 405 on the armature 410 out of contact with contact 403.

The combined value of the resistance of the coils 401 and the resistance 412 is such that predetermined normal current flows so that the train will obtain clearance though if desired the resistance 412 may be omitted 110 should the resistance of the coils 401 be sufficient.

When the train comes into contact with track contact 1 which is a warning contact the circuit of the generator 32 is completed through contact 1 wire 409 and the coils 402 in parallel with a path through contact plate 417, contact 416, wire 415, resistance 414, and wire 408 to the rails and the frame of the locomotive. The direction of the current through the coils 402 is such that the armature 407 is moved into the open position and breaks contact with the contact 406.

The value of the resistance of the coils 402 and the resistance 413 combined is such that predetermined normal current flows so that the train will obtain clearance though if desired the resistance 413 may be omitted 125 should the resistance of the coils 402 be sufficient.

Having entered the loop the driver 5 operates his commutator switch 100 and so switches into circuit the compensating resistance 65 and reverses the connection of the generator 32 to the shoe 10. When the train again comes into contact with the track contact 1 the circuit of the generator 32 is completed with the addition in the circuit of the compensating resistance 65 and 10 through contact 1, wire 409, coils 402, the rails and the frame of the locomotive. The direction of the current is now such that the armature 407 is moved into the closed position in which the insulated contact plate 15 417 effects contact with the contact 416 and so completes a parallel path for the current through wire 415, resistance 414, wire 408, and the rails.

The resistance of the track portion of the 20 path of the current is thus reduced to such an extent as, with the increased resistance of the train portion of the path due to the compensating resistance 65, to cause the flow of current of predetermined normal value, 25 so that the train obtains clearance.

Finally when the train again comes into contact with the stopping contact 2 the circuit of the generator 32 is again completed if armature 407 has been moved on contact 30 with the track contact 1 to effect contact with contact 406 through the coils 401 and the resistance 412.

The direction of flow of current through the coils 401 however being reversed the 35 armature 410 is moved so that its insulated contact plate 405 contacts with contact 403 thereby switching into parallel circuit the resistance 404 so as to compensate for the resistance 65 inserted in the circuit by the 40 commutator switch 100. Current of predetermined value accordingly flows so that the train obtains clearance and is enabled to proceed.

It will be seen that if the driver omits to 45 operate the commutator switch 100 when on the loop the armature 407 would not be moved into the closed position to contact with contact 406 by contact of the locomotive with the track contact 1 so that the train 50 would be stopped on coming into contact with the track contact 2.

Each of the armatures of the polarized 55 relays hereinbefore described is adapted to remain in the position into which it is switched when a train makes contact with a track contact, until the polarized relay in question is so traversed by current as to reverse the position of the armature.

In order to protect a train when just 60 entering a stretch of track provided with train protecting apparatus according to this invention, from the possibility of its being run into by a following train it is intended that the train shall be otherwise protected as by 65 means of interlocked signals or the like

when entering on a terminal section until it has proceeded sufficiently far along that section to be properly protected by the train protecting apparatus relating to the stretch of track in question. At a terminal section 70 the contacts (1, 2, 3) at the entering end of the section are preferably followed closely by the corresponding contacts of the intersecting section in order that a train entering the system may as soon as possible obtain 75 the full protection of the system as it will as soon as it has passed over a sufficient distance beyond the entering contacts of the first intersecting section to cause a train following it to be stopped automatically by 80 the entering contacts of the terminal section before colliding with the train that has first entered the system even if the last mentioned train be stopped after travelling over the said sufficient distance; consequently it is 85 advisable to extend the protection afforded, by means such as interlocking signals, so that any train entering the stretch of track is protected thereby until it has traversed the aforesaid sufficient distance beyond the 90 entering contacts of the first intersecting section.

The means for applying the brakes on the train consist preferably of one or more cylinders provided with one or more pistons 95 or the like suitably connected with the lever, or the like by which the brakes on the train are applied the arrangement being such that, upon failure of the electrical restraint on the movement of a valve fluid pressure will be 100 caused to act on the piston or pistons so that the brakes are applied on the train. Each train should be fitted with continuous automatic brakes.

The means for shutting off the motive 105 power by which the train is driven may be arranged in a manner similar to that mentioned above for applying the brakes or, if desired, the brakes may be applied and the power of the train shut off by means of only 110 one cylinder and piston, or the like.

Various modifications may be made in the apparatus without departing from the scope of the invention. For example wherever suitable, rails or other metallic conductors 115 may be substituted for earth conductors and vice versa also other metallic conductors may be substituted for rails.

It will be obvious that parts of the apparatus described herein may be in some cases 120 multiplied or omitted.

What I claim and desire to secure by Letters Patent of the United States is:—

1. Train-controlling apparatus comprising an electromagnetic device adapted in accordance with two conditions as to electrification to cause its movable part to occupy two different positions, a danger-indicating means carried by a locomotive, a direction-corresponding means carried by said loco- 125 130

motive and intended to be moved when the direction of facing and of travel of said locomotive is reversed, a traffic-controlling contact on the track adapted on contact therewith of said locomotive facing and traveling in one direction to enable said direction-corresponding means when in one position to cause said electromagnetic device to be in one of said conditions as to 10 electrification and adapted on contact therewith of said locomotive facing and traveling in the opposite direction to enable said direction-corresponding means when in the other position to cause said electromagnetic device 15 to be in the other of said conditions as to electrification, means adapted to reverse the direction of facing of said locomotive, and means adapted to cause the operation of said danger-indicating means on said locomotive 20 if, after the reversal of the facing of said locomotive, the direction of running of said locomotive is reversed without a corresponding movement of said direction-corresponding means. 25 2. Train-controlling apparatus comprising an electromagnetic device adapted in accordance with two conditions as to electrification to cause its movable part to occupy two different positions, a danger-indicating means carried by a locomotive, a direction-corresponding means carried by said locomotive and intended to be moved when the direction of facing and of travel of said locomotive is reversed, a traffic-controlling contact on the track adapted on contact therewith of said locomotive facing and traveling in one direction to enable said direction-corresponding means when in one position to cause said electromagnetic device 30 to be in one of said conditions as to electrification and adapted on contact therewith of said locomotive facing and traveling in the opposite direction to enable said direction-corresponding means when in the other 35 position to cause said electromagnetic device to be in the other of said conditions as to electrification, reversing means on the track adapted to reverse the direction of facing of said locomotive, a first checking track contact and a second checking track contact both in proximity to said reversing means and adapted to be encountered successively by said locomotive when said locomotive is approaching said reversing means, and an 40 electro-responsive device on the track connected to said second checking track contact and adapted to be, when said locomotive makes contact with said second checking track contact, put into one condition as to 45 electrification when said direction-corresponding means is in one position and into another condition as to electrification when said direction-corresponding means is in the other position, and adapted, when in the 50 condition as to electrification so produced

when said direction-corresponding means is in the position corresponding to the approach of said reversing means by said locomotive, to cause its movable part to occupy a position in which it is adapted to cause 70 said first checking track contact to bring about the operation of the danger-indicating means on a similarly equipped locomotive in contact therewith, and, when in the condition as to electrification so produced 75 when said direction-corresponding means is in the position corresponding to the leaving of said reversing means by the first mentioned locomotive, to cause its movable part to occupy a position in which it is adapted 80 to prevent said first checking track contact from bringing about the operation of said danger-indicating means on the first mentioned locomotive. 85 3. Train-controlling apparatus comprising on a locomotive a danger-indicating means and a direction-corresponding means intended to be caused to occupy one position when said locomotive faces and travels in one direction and another position when said locomotive faces and travels in the opposite direction, and on the track, a traffic-controlling contact adapted to come into contact with by said locomotive, means connected with said traffic-controlling contact and adapted, when said locomotive is in contact with said traffic-controlling contact and is facing and traveling in one direction and said direction-corresponding means is in one of its said positions, to co-operate with said direction-corresponding means in producing one traffic-controlling effect, and, when said locomotive is in contact with said traffic-controlling contact and is facing and traveling in the opposite direction and said direction-corresponding means is in the other of its said positions, to co-operate with said direction-corresponding means in producing another traffic-controlling effect, reversing means adapted to reverse the direction of facing of said locomotive, and means adapted to cause the operation of said danger-indicating means on said locomotive if, after the reversal of the facing of said locomotive, the direction of running of said locomotive is reversed and said direction-corresponding means is not in the position corresponding to the reversed direction of running. 115

4. Train-controlling apparatus comprising on a locomotive a danger-indicating means and a direction-corresponding means intended to be caused to occupy one position when said locomotive faces and travels in one direction and another position when said locomotive faces and travels in the opposite direction, and, on the track, a traffic-controlling contact adapted to come into contact with by said locomotive, means connected with said traffic-controlling contact, 120

125

130

- and adapted, when said locomotive is in contact with said traffic-controlling contact and is facing and traveling in one direction and said direction-corresponding means is in one of its said positions, to co-operate with said direction-corresponding means in producing one traffic-controlling effect, and, when said locomotive is in contact with said traffic-controlling contact and is facing and traveling in the opposite direction and said direction-corresponding means is in the other of its said positions, to co-operate with said direction-corresponding means in producing another traffic-controlling effect, 5
- 15 reversing means adapted to reverse the direction of facing of said locomotive, a first checking track contact and a second checking track contact both in proximity to said reversing means and adapted to be encountered successively by said locomotive when said locomotive is approaching said reversing means, and an electro-responsive device connected to said second checking track contact and adapted to be, when said locomotive makes contact with said second checking track contact, put into one condition as to electrification when said direction-corresponding means is in one of its said positions and into another condition 20 as to electrification when said direction-corresponding means is in the other of its said positions, and adapted, when in the condition as to electrification so produced when said direction-corresponding means is in the 25 position corresponding to the approach of said reversing means by said locomotive, to cause its movable part to occupy a position in which it is adapted to cause said first checking track contact to bring about the operation of the danger-indicating means on a similarly equipped locomotive in contact therewith, and, when in the condition as to electrification so produced when said direction-corresponding means is in the 30 position corresponding to the leaving of said reversing means by the first mentioned locomotive, to cause its movable part to occupy a position in which it is adapted to prevent said first checking track contact from bringing about the operation of said danger-indicating means on the first mentioned locomotive.
5. Train-controlling apparatus comprising on a locomotive a danger-indicating means adapted to operate to indicate danger except when energized by current of a predetermined strength and a direction-corresponding means intended to be caused to occupy one position when said locomotive faces and travels in one direction and another position when said locomotive faces and travels in the opposite direction, and, on the track, a traffic-controlling track contact adapted to come into contact with by said locomotive, traffic-controlling means connected with said traffic-controlling contact and adapted, when said traffic-controlling means occupies a certain position and said locomotive is in contact with said traffic-controlling contact and is facing and traveling in one direction, to co-operate with said direction-corresponding means in causing said danger-indicating means to be energized by current of said predetermined strength if said direction-corresponding means is in one of its said positions but not so to co-operate with said direction-corresponding means if said direction-corresponding means is in the other of its said positions reversing means adapted to reverse the direction of facing of said locomotive, a first checking track contact and a second checking track contact both in proximity to said reversing means and adapted to be encountered successively by said locomotive when said locomotive is approaching said reversing means, an electro-responsive device connected to said second checking track contact and adapted to be, when said locomotive makes contact with said second checking track contact, put into one condition as to electrification when said direction-corresponding means is in one position and into another condition as to electrification when said direction-corresponding means is in the other position, and adapted, when in the condition as to electrification so produced when said direction-corresponding means is in the position corresponding to the approach of said reversing means by said locomotive, to cause its movable part to occupy a position in which it is adapted to cause said first checking track contact to bring about the operation of the danger-indicating means on a similarly equipped locomotive in contact therewith, and, when in the condition as to electrification so produced when said direction-corresponding means is in the position corresponding to the leaving of said reversing means by the first mentioned locomotive, to cause its movable part to occupy a position in which it is adapted to prevent said first checking track contact from bringing about the operation of said danger-indicating means on the first mentioned locomotive, and an electro-responsive device connected to said first checking track contact and adapted, when the last mentioned movable part is in the last mentioned position and the first mentioned locomotive is in contact with said first checking track contact, to be, by said direction-corresponding means, caused to be in one condition as to electrification when said direction-corresponding means is in one of its said positions and in another condition as to electrification when said direction-corresponding means is in the other of its said positions and in both cases to co-operate 55 60 65 70 75 80 85 90 95 100 105 110 115 120 125 130

with said direction-corresponding means in causing said danger-indicating means on the first mentioned locomotive to be energized by current of said predetermined strength.

6. Train protecting apparatus comprising on a train an electro-responsive device whose movable part is adapted to occupy a line-clear position only when current of a predetermined strength energizes said electro-responsive device, a contacting device, a generator of electricity, a circuit portion including said electro-responsive device and said contacting device and said generator of electricity, and direction-corresponding means adapted to occupy different positions in accordance with the opposite directions of running of said train and thereby to connect said contacting device with one pole of said generator when said train is traveling in one direction and with the other pole of said generator when said train is traveling in the opposite direction, and on the track a traffic-controlling device adapted to occupy a line-clear and a danger position, a track contact adapted to contact with said contacting device, an electro-responsive device whose movable part is adapted to occupy two different positions in accordance with the directions of current energizing said electro-responsive device on the track and in one position to cause the flow of current of said predetermined strength through said electro-responsive device on the train to be dependent on the position of said traffic-controlling device and in the other position to cause the flow of current of said predetermined strength through the last mentioned electro-responsive device to be independent of the position of said traffic-controlling device.

7. In a train protecting apparatus, track sections comprising contiguous end sections and an intermediate intersecting section, two sets of track contacts at the two ends

respectively of each section, polarized switching relays arranged in pairs at the two ends of each of the sections and operatively connected to the track contacts, the relays of the intersecting section being designed to test the positions of the relays commanding the contiguous ends of the end sections.

8. In a train protecting apparatus, two contiguous track sections and an intermediate intersecting section, two sets of track contacts at the two ends respectively of each section, two relays for each section operatively connected to the two sets of contacts respectively of that section, the relays of the intersecting section being designed to test the positions of the armatures of the relays commanding the contiguous ends of the end sections.

9. Train-controlling apparatus comprising on a train a danger-indicating means and on the track two adjacent track sections and a section intersecting said adjacent sections and, for each section, track contacts at the two ends respectively of the section and two electro-responsive traffic-controlling devices adapted to control the passage of trains over the two ends respectively of the section and connected to the track contacts at the two ends of the section and adapted to be, on contact of a train with a track contact connected therewith, so set as to prevent the admission of a train into the section at the corresponding end, each of the two traffic-controlling devices adapted to control the passage of trains over the adjacent ends of the adjacent sections being adapted when not set as aforesaid to cause the operation of said danger-indicating means on said train when said train makes contact with a track contact located at the adjacent end of said intersecting section.
